B. EHHRMAN

SPRING CLAMP

Filed Jan. 27, 1923

INVENTOR

BERTHA EHHRMAN,
by James L. Hopkins, ATTORNEY.

UNITED STATES PATENT OFFICE.

BERTHA EHRMAN, OF ST. LOUIS, MISSOURI.

SPRING CLAMP.

Application filed January 27, 1923. Serial No. 615,225.

To all whom it may concern:

Be it known that I, BERTHA EHRMAN, a citizen of the United States of America, residing at the city of St. Louis, in the State of Missouri, have invented certain new and useful Improvements in Spring Clamps, of which the following is a specification, reference being had therein to the accompanying drawing.

10 My invention relates to improvements in spring clamps. It has for its object to provide an extensible and adjustable clamp particularly adapted to securing a cloth covering upon a table or ironing board.

15 *Drawings.*

In the drawing—

Fig. 1 is a perspective view of a clamp embodying my invention.

20 Figs. 2, 3 and 4 are plan views of said clamp in various adjustments.

Description.

I have illustrated my clamp as comprising the gripping members A and B, secured together by an intermediate tensioning spring 15, said spring 15 being secured to the member A by the eye 16 and to the member B by the eye 17.

30 The members A and B are identical in structure except as to the length of the loop member, which is indicated by the numeral 8 (in the member A) and by the numeral 13 (in the member B).

35 The U-shaped body 5 is provided with the hooks 6, the neck 7, the long loop 8 and short loop 9, all formed from a single piece of wire. Likewise the member B comprises the U-shaped body 10, having the hooks 11, the neck 12, the long loop 13 and short loop 14.

40 Assembled as in Fig. 1, the device has its greatest spread between the hooks 6 and 11.

In Fig. 2 the clamp has been shortened by 45 shifting the eye 17 into the loop 14.

Fig. 3 illustrates still greater shortening, the eye 17 being shifted back into the loop 13 and the eye 16 having been shifted into engagement with the loop 9.

In Fig. 4 I illustrate the shortest possible 50 adjustment of the members, the eye 16 engaging with the loop 9 and the eye 17 engaging with the loop 17.

Mode of operation.

55 The clamp thus described is intended to be used upon the bottom of a table or ironing board, the top of which table or ironing board is provided with a pad or cloth covering or both, and the edges of which pad or covering extend into contact with the outer edges of the table or ironing board. The clamp of my invention is then applied by being placed beneath the covered structure, the hooks 6 and 11 extending upwardly and 60 holding the pad or cloth in contact with the edge of the board or table.

Claims.

I claim:—

1. A spring clamp comprising two U-shaped body members each having hooks, a long loop and a short loop; and a tensional spring connecting said body members and having eyes arranged to engage with the 75 long loop or the short loop of either member.

2. A spring clamp comprising two U-shaped body members each having hooks, a long loop and a short loop; and a tensional 80 spring connecting said body members and having eyes arranged to engage with the long loop or the short loop of either member, each of said body members being formed of a single piece of wire.

85 In testimony whereof I have hereunto affixed my signature.

BERTHA EHRMAN.
